UNITED STATES PATENT OFFICE.

RUDOLF E. HELLMUND, OF PITTSBURGH, PENNSYLVANIA, ASSIGNOR TO WESTINGHOUSE ELECTRIC AND MANUFACTURING COMPANY, A CORPORATION OF PENNSYLVANIA.

SYSTEM OF CONTROL.

1,266,592.

Specification of Letters Patent. Patented May 21, 1918.

Application filed March 4, 1916. Serial No. 82,094.

To all whom it may concern:

Be it known that I, RUDOLF E. HELLMUND, a subject of the Emperor of Germany, and a resident of Pittsburgh, in the county of Allegheny and State of Pennsylvania, have invented a new and useful Improvement in Systems of Control, of which the following is a specification.

My invention relates to systems of control and especially to the automatic control of electric railway vehicles and the like that are adapted to regenerative operation.

One object of my invention is to provide a system of the above-indicated character wherein novel means is employed for effecting a uniform rate of deceleration of momentum-driven dynamo-electric machines.

More specifically stated, it is an object of my invention to provide a relay device of the motor type for automatically governing the operation of dynamo-electric machines during the regenerative period in particular the magnetic circuit of the relay device, in accordance with one modification, being initially saturated to a predetermined greater degree than the magnetic circuit of the main machine or machines, and the two magnetic circuits in question being subsequently saturated to substantially the same degree, whereby the initial rate of deceleration is less than the subsequent rate.

A further object of my invention is to provide a system of control for a locomotive or motor-car embodying relatively simple and reliable means for enabling the train operator to vary the rate of acceleration or deceleration in accordance with the weight of train to be handled.

In the prior art, in order to obtain uniform deceleration of a momentum-driven dynamo-electric machine, it has been proposed to employ a limit switch of the solenoid type and to adjust the active values of the actuating coils of the device at different times during the regenerative period, as set forth in a copending application of R. E. Hellmund and N. W. Storer, Serial No. 77,428, filed Feb. 10, 1916, and assigned to the Westinghouse Electric & Manufacturing Company. It is explained in that applica-

tion that, in order to avoid excessive armature currents and consequent excessive heating of the machine, as well as to avoid an undesirably high ratio of armature ampere-turns to field-winding ampere-turns and resultant liability to "flash-over" conditions, in some cases it is desirable to initially provide a lower rate of deceleration than during the latter portion of the regenerative period.

According to my present invention, I provide a relay device of the motor type having its armature and field winding respectively energized in accordance with the currents traversing the main armature and the main field winding during regenerative operation, and I provide regulating means in connection with the relay device for either manually or automatically varying the energization of the relay device elements, when the machines to be governed are subject to "flash-over" troubles under initial regenerative conditions, in such manner that the magnetic circuit of the relay device is initially saturated to a predetermined greater degree than the magnetic circuit of the main machine or machines and is subsequently saturated to substantially the same degree, thereby permitting an initial rate of deceleration for any desired length of time that is less than the decelerating rate during the remainder of the regenerative period. Moreover, the rate of automatic train acceleration or deceleration may be varied at the will of the train operator, as herein-after more fully set forth.

My invention may best be understood by reference to the accompanying drawings, wherein Figure 1 is a diagrammatic view of the main circuits of a system of control to which is applied a system of interconnections with my relay device; Fig. 2 is a diagrammatic view of the auxiliary governing circuits for various switches that are shown in Fig. 1 and are governed in accordance with the operation of the relay device; Fig. 3 is a diagrammatic view, corresponding to Fig. 2, of a modification of my invention; and Fig. 4 is a detailed diagrammatic view of a complete switch that is employed in the system of Fig. 1.

Referring to Fig. 1 of the drawing, the regenerative system that is shown comprises a plurality of suitable supply-circuit conductors respectively marked "Trolley" and "Ground"; a plurality of dynamo-electric machines respectively having armatures A1 and A2 and field-magnet windings F1 and F2 of the series-type; a plurality of main-circuit resistors FR1 and FR2 that are respectively connected in circuit with the main armatures A1 and A2; a motor-generator set or dynamotor having a pair of armatures M and G that may be mechanically connected by a shaft s1 or in any other suitable manner, and a common field-magnet winding DF for the armatures M and G; a plurality of switches R1 to R6, inclusive, and RR1 to RR6, inclusive, for short-circuiting certain sections of the resistors FR1 and FR2, respectively; and my relay device RD.

The relay device RD, more clearly illustrated in Fig. 2, is shown as comprising an armature RA, a suitable field-magnet winding RF, a pulley P that is mounted on the shaft s2 of the armature RA, a weight that is adapted to act upon the pulley P in opposition to the backward-actuating torque of the armature RA, and a drum controller D1 that is employed for the purpose of regulating the main-circuit resistors FR1 and FR2 in a manner to be described.

The relay device armature RA is connected, through a suitable switch S, in parallel relation to a translating device, such as a resistor 9, that is inserted in circuit intermediate the main armature A1 and the main field winding F1, while the relay device field winding RF is connected in series relation with a suitable variable resistor 10 across the main field winding F1. A plurality of switches 1, 2 and 3 are provided for varying the active value of the resistor 9 and may be open during the initial portion of the regenerative period, and a plurality of suitable switches 4, 5 and 6 are adapted to short-circuit sections of the resistor 10 and may be closed during the first portion of regenerative operation. As indicated by the arrow, the weight W is adapted to act in opposition to the relay device armature RA and thereby actuate the drum controller D1 through its successive positions in accordance with the torque conditions of the relay device, which are controlled in a manner to be set forth later. It will be understood that any other suitable relay device of the motor-type may be substituted for that herein shown.

The main armature A1 is connected in series relation with the variable translating device 9 and the main-circuit resistor FR1 between the supply-circuit conductors Trolley and Ground, while the other main armature A2, in conjunction with the main-circuit resistor FR2, is connected in par-

allel relation with the circuit just mentioned. The main field winding F1 is included in a circuit that also comprises the generator armature winding G of the dynamotor and the resistor FR1, while the other main field winding F2 is also adapted to be energized from the generator armature winding G through the variable resistor FR2. Each main field winding and the generator armature winding are thus connected in parallel relation to one of the main-circuit resistors. The motor armature winding M may be connected between the trolley and the junction-point of the main-circuit resistors FR1 and FR2, while the dynamotor field-magnet winding DF may be connected across the armature M, or any other suitable type or combination of field windings may be employed, as will be understood.

Tracing the above-mentioned circuits in detail, the regenerative or main-armature circuit, is established from the supply-circuit conductor Ground through conductor 40 to junction-point 41, where the circuit divides, one branch including resistor FR1, translating device 9, armature A and a second junction-point 42, and the other branch traversing resistor FR2 and armature A2 to the junction-point 42, whence a common circuit is completed through conductor 43 to the trolley.

The exciting or main-field-winding circuit, is established from the positive terminal of the generator armature winding G through conductor 40 to the junction-point 41, where the circuit divides, one branch traversing resistor FR1 and field winding F1 to another junction-point 44, and the other branch including resistor FR2, field winding F2 and the junction-point 44, whence a common circuit is completed to the negative terminal of the generator armature G.

An auxiliary circuit is established from the trolley through conductor 43, parallel-related auxiliary motor armature M and field winding DF, and conductor 40 to ground.

The main-circuit connections just recited form no part of my present invention, being employed for illustrative purposes only, but are fully set forth and claimed in my co-pending application, Serial No. 44,413, filed Aug. 9, 1915. The general operation of the relay device RD will first be set forth and then the specific circuit connections that are effected by such operation will be described in connection with Fig. 2.

It will be understood that, during the regenerative period, the armature or regenerated current is preferably maintained substantially constant, as is more or less customary, while the field-winding current is continuously increased, as the machine speed decreases, by means of the gradual exclusion of the main-circuit resistors FR1 and FR2

from circuit. Moreover, in accordance with one method of operation, at first the switches 1, 2 and 3 are open, whereby the entire translating device 9 is active, while the switches 4, 5 and 6 are initially closed to completely short-circuit the auxiliary resistor 10. As the main-machine speed decreases during the regenerative period, the switches 1, 2 and 3 are successively closed, thereby gradually decreasing the effective voltage that is impressed upon the relay device armature RA; whereas the switches 4, 5 and 6 are gradually opened to decrease the effective energization of the relay device field winding RF from the main field winding F1. Inasmuch as the torque of a dynamo-electric machine is proportional to the product of the armature current and effective field flux, it follows that the torque of the relay device RD gradually decreases as the regenerative operation progresses, whereby the torque of the regenerating machines is initially less than the subsequent torque, or, in other words, the initial rate of deceleration is less than the subsequent rate, as explained more fully hereinafter, which is desirable when the momentum-driven main machine is initially liable to "flash-over" trouble.

The design of parts of the relay device RD with respect to the main dynamo-electric machines is such that initially, that is, before the manipulation of the switches 1 to 6, inclusive, from the illustrated positions, the magnetic circuit of the relay device is saturated to a predetermined greater degree than the magnetic circuit of the main machines, whereas, upon the manipulation of the switches 1 to 6, inclusive, the degree of saturation decreases to a point where it substantially equals the degree of saturation of the main machines. Thus, during the latter portion of the regenerative period, the relay device governs the operation of the main-circuit resistors FR1 and FR2 to maintain a substantially uniform rate of deceleration of the main machines, whereas, initially, the operation of the relay device, by reason of the relatively great saturation of the magnetic circuit thereof, is such as to produce a relatively low value of regenerated current and, consequently, a relatively low rate of deceleration.

It will be understood, that, when the relay device magnetic circuit is saturated to the same degree as the main machine magnetic circuit, the device will operate to maintain a substantially constant torque of the main machines, but when the relay device, by reason of its different magnetic characteristics, becomes more highly saturated than the main machines, the device lags in its action, a greater change of field current is necessary to obtain action of the device, and, as a result, the main machine current is allowed

to decrease to lower values before the device moves the controller forward. Thus, by suitable adjustment of the relay device circuits, the train operator may vary the rate of acceleration or deceleration in accordance with the weight of train to be handled.

Referring to Fig. 2, the auxiliary governing system shown comprises the complete relay device RD; the actuating coils of the switches R1 to RR6, inclusive, and a suitable source of energy, such as a battery B, for energizing the various actuating coils in accordance with the position of the control drum D1, which is adapted to occupy a plurality of operative positions *a* to *f*, inclusive.

Assuming that the circuit connections are as shown in Fig. 1 and that regeneration has been started in any suitable manner, the operation of the relay device RD may be set forth as follows: When the regenerated current has decreased a slight amount that corresponds to the setting of the relay device, the torque of the device is temporarily overcome by the weight W or its equivalent, whereby the control drum D1 is actuated to its initial operative position *a*, whereupon, a control circuit is established from one terminal of the battery B through conductor 20, control finger 21, contact segment 22, and control fingers 23 and 24 of the drum controller, whence circuits are respectively completed through conductors 25 and 26 to the actuating coils of the switches R1 and RR1 and conductor 27 which is connected to the negative battery terminal.

Consequently, the switches R1 and RR1 are closed to short-circuit predetermined portions of the main resistors FR1 and FR2, whereby the torque of the relay device RD again rises temporarily to a sufficient value to overcome the action of the weight W and thus hold the controller D1 in position *a*. It will be understood that suitable position-accentuating means, such as the customary star-wheel and spring-pressed pawl, are preferably employed in connection with the controller D1 to aid in stopping the drum in the proper positions. However, as will be appreciated, the current soon decreases to the critical value, whereupon the weight W again actuates the controller D1 in opposition to the relay-device torque to the second position *b*, wherein control fingers 28 and 29 engage the contact segment 22, and the actuating coils R2 and RR2 are energized to effect the short-circuit of further portions of the resistors FR1 and FR2.

Without further description, it will be understood that the control drum D1 is intermittently actuated through its successive positions to thus gradually effect the exclusion of the resistors FR1 and FR2 from circuit.

During the above-mentioned operation of

the control drum RD1, the switches 1, 2 and 3 may be manually manipulated to thus gradually short-circuit portions of the translating device 9, while the switches 4, 5 and 6 5 may be successively opened to gradually include the auxiliary resistor 10 in circuit, for the regulating purposes hereinbefore set forth. It should be observed that the switches 1 to 6, inclusive, may be operated 10 from a master controller, or otherwise, to vary the initial and subsequent rates of deceleration as the train operator sees fit, instead of first having the switches in the illustrated positions, thus permitting an adjustment 15 of the relay device RD to meet various service conditions; for instance, handling different loads by a locomotive.

If desired, instead of manually manipulating the switches 1 to 6, inclusive, at the 20 will of the train-operator, such switches may be of the same type as the switches R1 to RR6, inclusive, and, in that case, may be automatically controlled by the relay device RD and suitably interlocked with the resistors 25 or short-circuiting switches to operate at the desired times. Such a system is illustrated in Fig. 3, wherein the circuits shown comprise, in addition to those that are illustrated in Fig. 2, a plurality of actuating coils 30 for switches 11 to 16, inclusive, that respectively correspond to switches 1 to 6, inclusive, of Fig. 1, together with certain electrical interlocks that are associated with, and adapted to be actuated by, the respectively 35 designated switches in accordance with the familiar type of construction that is illustrated in Fig. 4, and additional contact members of a drum controller D2 that corresponds to the drum controller D1.

40 Assuming that the main-circuit connections are as illustrated in Fig. 1 and that regenerative operation has been inaugurated, the control drum D2 will be moved to its initial operative position *a* in a similar manner to that set forth in connection with Fig. 45 2. However, in the "off" position of the control drum, a circuit is established from the battery through conductor 20, control fingers 21 and 29, which are bridged by contact segment 22, conductor 30 and three parallel-related circuits respectively comprising interlocks 11—out and R3—out and the actuating coil of switch 14, interlocks 12—out and R4—out and the actuating coil 50 of the switch 15 and interlocks 13—out and R5—out and the actuating coil of the switch 16, whence a common circuit is completed through the negative conductor 27. The auxiliary resistor 10 is thus initially short-circuited, as previously described in connection with Fig. 1. On the other hand, the actuating coils of the switches 11, 12 and 13 55 are not energized by reason of the inclusion in their respective circuits of interlocks R3—in, R4—in and R5—in.

The various pairs of actuating coils of the resistor short-circuiting switches are again energized in accordance with the operation of the control drum, and, in addition, after the initial period of relatively low-rate deceleration and, when the switch R3 has been closed, a circuit is completed from the conductor 30 through conductor 31, interlock R3—in and the actuating coil of the switch 11 to the negative conductor 27. Upon the subsequent closure of switches R4 and R5, by reason of the above-described intermittent operation of the control drum D2, the actuating coils of the switches 12 and 13 are respectively energized by reason of the inclusion of interlocks R4—in and R5—in in their respective circuits, thereby successively closing the switches 12 and 13 to short circuit further sections of the resistor 9. 70 75 80

As the switches 11, 12 and 13 or as the switches R3, R4 and R5 are closed, the circuits of the actuating coils of the switches 14, 15 and 16 are respectively opened by the corresponding interlocks, thereby gradually inserting the auxiliary resistor 10 in circuit for the purpose already explained. 90

The operation of the switches 11 to 16, inclusive, is thus made automatically dependent upon the operation of the relay device RD and the consequent closure of certain resistor short-circuiting switches. 95

I do not wish to be restricted to the specific circuit connections or location and arrangement of parts herein set forth, as various modifications thereof may be effected without departing from the spirit and scope of my invention. I desire, therefore, that only such limitations shall be imposed as are indicated in the appended claims. 100 105

I claim as my invention:

1. In a system of control, the combination with a main dynamo-electric machine having an armature and a field winding, of a motor-type relay device having its magnetic circuit saturated to substantially the same degree as the magnetic circuit of the main machine during a predetermined operating period, and means governed by said relay device for varying the main-machine circuit-resistance, whereby a substantially constant rate of change of main-machine speed is obtained. 110 115

2. In a system of control, the combination with a main dynamo-electric machine having an armature and a field winding and adapted for regenerative operation, of a motor-type relay device having its magnetic circuit saturated to substantially the same degree as the magnetic circuit of the main machine during a predetermined portion of the regenerative period, and means governed by said relay device for decreasing the main-machine circuit-resistance, whereby a substantially constant rate of 120 125 130

deceleration of main-machine speed is automatically obtained.

3. In a system of control, the combination with a main dynamo-electric machine having an armature and a field winding, of a motor-type relay device having its magnetic circuit saturated to a predetermined greater degree than the magnetic circuits of the main machine during a predetermined operating period, and means governed by said relay device for varying the main-machine circuit connections.

4. In a system of control, the combination with a main dynamo-electric machine having an armature and a field winding and adapted for regenerative operation, of a motor type relay device having its magnetic circuit saturated to a predetermined greater degree than the magnetic circuit of the main machines during a predetermined portion of the regenerative period, and means governed by said relay device for decreasing the main-machine circuit-resistance.

5. In a system of control, the combination with a main dynamo-electric machine having an armature and a field winding, of a motor-type relay device, and means for saturating the magnetic circuit thereof to a predetermined greater degree than, and to substantially the same degree as, the magnetic circuit of the main machine during different portions of the operating period thereof.

6. In a system of control, the combination with a main dynamo-electric machine having an armature and a field winding and adapted for regenerative operation, of a motor-type relay device, means for saturating the magnetic circuit thereof to a predetermined greater degree than, and to substantially the same degree as, the magnetic circuit of the main machine during a certain initial and the subsequent portions of the regenerative period, respectively, and means governed by said relay device for varying the main-machine circuit-resistance, whereby the initial rate of main-machine deceleration is less than the subsequent rate.

7. In a system of control, the combination with a main dynamo-electric machine having an armature and a field winding and adapted for regenerative operation, of a motor-type relay device having its windings respectively energized in accordance with the main armature current and the main field-winding currents, and means for saturating the magnetic circuit of said relay device to substantially the same degree as the magnetic circuit of the main machine during a predetermined portion of the regenerative period.

8. In a system of control, the combination with a main-dynamo-electric machine having an armature and a field winding and adapted for regenerative operation, of a motor-type relay device having an armature and a

field winding respectively energized in accordance with the currents traversing the main armature and the main field winding, respectively, and means for saturating the magnetic circuit of said relay device to a predetermined greater degree than the magnetic circuit of the main machine during a predetermined portion of the regenerative period.

9. In a system of control, the combination with a main dynamo-electric machine having an armature and a field winding and adapted for regenerative operation, of a motor-type relay device having an armature and a field winding respectively energized in accordance with the currents traversing the main armature and the main field winding, respectively, and means for saturating the magnetic circuit of said relay device to a predetermined greater degree than, and to substantially the same degree as, the magnetic circuit of the main machine during a certain initial and the subsequent portions of the regenerative period, respectively, and means governed by said relay device for varying the main-machine circuit-resistance, whereby the initial rate of main machine deceleration is less than the subsequent rate.

10. In a system of control, the combination with a main dynamo-electric machine having an armature and a field winding and adapted for regenerative operation, of a motor-type relay device having an armature and a field winding respectively energized in accordance with the currents traversing the main armature and the main field winding, respectively, means governed by said relay device for varying the main-machine circuit-resistance as the machine speed decreases, and means for gradually varying the effective energization of the relay device armature and field windings to correspondingly decrease the effective torque of the relay device and increase the rate of deceleration of the main machine.

11. In a system of control, the combination with a main dynamo-electric machine having an armature and a field winding and adapted for regenerative operation, of a translating device connected in series relation with said armature, a motor-type relay device having an armature and a field winding respectively energized from said translating device and said main field winding, means governed by said relay device for decreasing the main machine circuit-resistance as the machine speed decreases, an auxiliary resistor connected in circuit with the relay device field winding, means for gradually increasing the active value of said auxiliary resistor, and means for decreasing the active value of said translating device as the main-machine speed decreases, whereby the initial rate of main-machine deceleration is less than the subsequent rate.

12. In a system of control, the combination with a main dynamo-electric machine having an armature and a field winding and adapted for regenerative operation, of a translating device connected in series relation with said armature, a motor-type relay device having an armature and a field winding respectively energized from said translating device and said main field winding, 10 means governed by said relay device for decreasing the main machine circuit-resistance as the machine speed decreases, an auxiliary resistor connected in circuit with the relay-device field winding, the magnetic circuit of 15 the relay device being initially saturated to a predetermined greater degree than the magnetic circuit of the main machine, means for gradually increasing the active value of said auxiliary resistor and means for decreasing 20 the active value of said translating device as the main machine speed decreases to effect saturation of said magnetic circuits to substantially the same degree, whereby the initial rate of main machine deceleration is 25 less than the subsequent rate.
13. In a system of control, the combination with a main dynamo-electric machine having an armature and a field winding and adapted for regenerative operation, of a 30 motor-type relay device having its operating windings respectively energized in accordance with the currents traversing the main armature and the main field winding, a variable main-circuit resistor, a plurality 35 of switches for excluding predetermined sections of said resistor from circuit, means governed by said relay device for closing said switches in a predetermined sequence, switching means for varying the effective 40 energizations of the relay-device operating windings, and interlocking means automatically dependent upon the movement of said switches for insuring predetermined operation of said switching means.
14. In a system of control, the combination with a main dynamo-electric machine having an armature and a field winding and adapted for regenerative operation, of a translating device connected in series relation with said armature, a motor-type relay device having an armature and a field winding respectively energized from said translating device and said main field winding, an auxiliary resistor connected in circuit with the relay-device field winding, a variable main-circuit resistor, a plurality of switches for excluding predetermined sections of said resistor from circuit, means governed by said relay device for closing 55 said switches in a predetermined sequence, interlocking means dependent upon the successive closure of certain of said switches for gradually decreasing the active value of said translating device, and interlocking 60 means dependent upon said gradual decrease 65

for gradually increasing the active value of said auxiliary resistor, whereby the later rate of deceleration automatically becomes greater than the initial rate.

15. In a system of control, the combination with a dynamo-electric machine having an armature and a field winding, of a motor-type relay device having its magnetic circuit saturated to bear a predetermined relation to the saturation of the main-machine magnetic circuit, and means governed by said relay device for changing the main-machine circuit connections to obtain predetermined operating torque conditions in the main machine. 70

16. In a system of control, the combination with a dynamo-electric machine having an armature and a field winding, of a motor-type relay device having the circuits of its operating windings respectively energized in accordance with the currents traversing the main armature and field winding, means governed by said relay device for effecting changes in the main-machine circuits, and means for varying the effective voltages impressed upon said operating windings to vary the rate of said changes. 80

17. In a system of control, the combination with a dynamo-electric machine having an armature and a field winding, of a motor-type relay device having its armature and field-winding circuits respectively energized in accordance with the currents traversing the main armature and field winding, means governed by said relay device for automatically effecting changes in the main machine connections, and means for varying the resistances of said relay-device circuits to vary the rate of said changes, whereby the rate of acceleration or deceleration of the main machine may be varied. 90

18. In a system of control, the combination with a dynamo-electric machine having an armature and a field winding, of a relay device having a plurality of operating windings respectively energized in accordance with predetermined armature and field-winding conditions, means governed by said relay device for effecting changes in the machine circuits, and separate means for influencing the effective voltages impressed upon said operating windings. 100

19. In a system of control, the combination with a dynamo-electric machine having an armature and a field winding, of a relay device having a plurality of operating windings respectively energized in accordance with predetermined armature and field-winding conditions, means governed by said relay device for effecting changes in the machine circuits, and means for differently varying certain circuit voltages to affect the operation of said relay device. 110

20. In a system of control, the combination with a dynamo-electric machine having 120

an armature and a field winding, of a relay device having a plurality of operating windings respectively energized in accordance with predetermined armature and field-winding conditions, means governed by said relay device for effecting changes in the machine circuits, and means for independently

influencing one of the operating-winding circuits of said relay device under predetermined conditions.

In testimony whereof, I have hereunto subscribed my name this 28th day of Feb. 1916.

RUDOLF E. HELLMUND.
